CLAIM

The ornamental design for a slicer for fruit and vegetable, as shown and described.

DESCRIPTION

FIG. 1 is a front perspective view of a slicer for fruit and vegetable, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is the slicer for fruit and vegetable in a state; and,

FIG. 10 is the slicer for fruit and vegetable in a state.

The dashed broken lines depict portions of the slicer for fruit and vegetable that form no part of the claim design.

1 Claim, 10 Drawing Sheets
